(57) CLAIM

The ornamental design for a pair of table tops, as shown and described.

DESCRIPTION

FIG. 1 is a perspective view of a pair of table tops according to the design, shown in environment;

FIG. 2 is a perspective view of the pair of table tops according to the design, shown in environment;

FIG. 3 is a top view of the pair of table tops of FIG. 2;

FIG. 4 is a front view of the pair of table tops of FIG. 2; and, FIG. 5 is a rear view of the pair of table tops of FIG. 2.

The broken lines that are included in the figures of the drawings denote aspects of the environment of the pair of table tops that form no part of the claimed design.

The bottom view, the right side view, and the left side view of the pair of table tops are excluded, because they are plain and unornamented and, therefore, form no part of the claimed design.
